ENCLOSURE FOR VARIABLE-SPEED ELECTRONIC PUMP DRIVE

Gilbert A. Gothing, Boylston, Mass., assignor to Ikor,
Incorporated, Burlington, Mass., a corporation of
Massachusetts

Filed July 17, 1968, Ser. No. 12,805

Term of patent 14 years

Int. Cl. D15—02

U.S. Cl. D65—1

FIG. 1.

FIG. 2.

FIG. 1 is a perspective is a perspective view of an enclosure for a variable-speed, electronic pump drive showing my new design, and

FIG. 2 is a rear perspective view.

The dominant features of my design reside in the portions shown in full lines. The drawing is stippled to indicate a color contrasting with the color of the finned portion of the design, but no specific colors are denoted.

I claim:

The ornamental design for an enclosure for a variable-speed electronic pump drive, substantially as shown and described.
